UNITED STATES PATENT OFFICE.

ABBY MARIA SHATTUCK, OF NEW YORK, N. Y.

GAME.

1,269,323.

Specification of Letters Patent. Patented June 11, 1918.

Application filed July 21, 1917. Serial No. 181,953.

To all whom it may concern:

Be it known that I, ABBIE M. SHATTUCK, a citizen of the United States, and resident of the borough of Manhattan, city, county, 5 and State of New York, have invented certain new and useful Improvements in Games, of which the following is a specification.

The device the subject of this invention 10 is a game, and I desire that it be understood that the game has as its definite purpose the development of the skill of the players in emphasizing the delicacy of touch, the approximation of value and an understanding 15 of the inertia of bodies of different weights and diameters. It will be seen, therefore, that this game is not a game of chance, but is rather one well adapted to develop in the 20 player skill and judgment that may be useful in connection with other games or useful work,

Primarily this game is intended as a pastime, and, therefore, I do not intend that it should be surrounded with complex rules, 25 but that rather it should be simplified to a series of operative actions, the successful performance of which will be possible by continued application or practice.

The following is what I consider a good 30 means of carrying out this invention and the accompanying drawings should be referred to for a complete understanding of the specification which follows.

In the drawings:—

Figure 1 shows a plan view of the game 35 board with one of the movable members in position.

Fig. 2 shows the series of movable members employed by each player.

Similar reference numerals indicate like 40 parts in all of the figures where they appear.

The member which I will refer to as a game board consists of a board of wood or 45 card board, fiber or other similar or satisfactory material, flat and approximately square as shown at 1.

Surrounding the edges of the board 1, are 50 rails or walls 2, 3, 4 and 5, one at each side of the board 1, and secured thereto and to each other.

Into the board 1, I introduce a plurality of recesses of different shapes and sizes, such recesses are indicated as follows: At 6

a small recess retains the movable member 55 at the start. At 7 a slightly larger recess is shown, and this recess is oval, another and larger oval recess is shown at 8, a round recess at 9, and two additional recesses at 10 and 11. 60

To make the game definite and interesting I have indicated these recesses by employing in relation to each a name or title. The recess 7 is termed a "lake," the recess 8 a "brook," 9 a "swamp," 10 "home," and 11 65 "police station."

Secured upon the board 1 are a plurality of baffles or rails arranged in pairs, and between each pair is a space sufficiently large for the largest movable member to pass, 70 and in describing the location of the baffles and the reference characters which apply thereto, I will refer to them in the order in which the game is played, and following the course of the dotted line A. 75

The members used in playing this game are shown in Fig. 2, and consist of a plurality of marbles or agates 12, 13, 14, 15 and 16, and it will be noted that they vary in size and consequently in weight. The 80 marbles are propelled along the course of the dotted line by means of a very thin pointer 17 which may be made of wood or other suitable material. The pointer should be round and tapered and the smallest end 85 should be used in propelling the marbles.

The player places one of the marbles, probably the larger marble 12, in the position shown in Fig. 1, and then lightly grasping the pointer or propeller 17 between the 90 thumb and fingers propels the marble by a series of pushing movements or strokes along the dotted line A. The marble is urged from between the barriers 18 downward and obliquely upward and then 95 through the barriers 19 to and through the barriers 20, 21, 22, 23, 24, 25, 26 and 27 to a point midway between the barriers 28 and 29, and then if sufficiently skilful the marble may be moved to the "home" recess indicated 100 at 10. It will be noted that the line of travel through the separate barriers is a circuitous path, which at different points comes into close approximation to the recesses 7, 8, 9, and 11, and should by any chance the 105 marble drop into one of these recesses the player is penalized by a loss of a turn or of a count.

The object of the game is for each player to move each of his five marbles of different weights and sizes along the course A from the start at 6 to home at 10, and other rules 5 being ignored the person who is successful reaches the "home" position with all five marbles wins the game.

To play the game successfully the game board should be placed in a flat and level 10 position, and although it is not possible to follow the dotted line at all times the line does serve as an indication of direction, the direction which must at all times be adhered to. Short cuts are not permissible, nor can 15 the passage through barriers in the reverse direction to that indicated be allowed.

The game may be modified by increasing or decreasing the number of barriers, by increasing or decreasing the size or number of 20 recesses or by any other change which may suggest itself in the operation of the game here described. I prefer the game to be constructed and played in the manner described.

Having carefully and fully described my 25 invention what I claim and desire to secure by Letters Patent is:—

1. A game consisting of a game board provided with a plurality of baffles and a plurality of movable members of different

sizes adapted to be propelled through said 30 baffles.

2. A game comprising a game board having a plurality of baffles arranged in pairs and a plurality of movable members adapted to be traversed in a circuitous passage 35 through said baffles.

3. A game board having a plurality of baffles arranged in pairs and angularly disposed to each other, a plurality of marbles of different weights adapted to be propelled 40 through said baffles and a pointer for propelling said marbles.

4. A game board provided with a plurality of recesses and a plurality of baffles arranged in pairs and secured to said board, said pairs of baffles being angularly disposed upon the surface of said board, and a plurality of marbles of different sizes adapted to be propelled in a circuitous line through 45 said baffles and means for propelling said marbles along said circuitous line.

Signed at New York City, county and State of New York this 8th day of July, 1917.

ABBIE MARIA SHATTUCK.
